CLAIM

The ornamental design for a double layer otoscope protective cap, as shown and described.

DESCRIPTION

FIG. 1 is a perspective view of a double layer otoscope protective cap, showing my new design;

FIG. 2 is a front elevation view thereof, the rear elevation view being a mirror image thereof, and the left and right elevation views are identical to the front elevation view;

FIG. 3 is a top plan view thereof; and,

FIG. 4 is a bottom plan view thereof.
